APPARATUS FOR FORMING CAN TOPS
AND LIDSLeonard W. Sturdy, London, Ontario, Canada
Application April 7, 1944, Serial No. 529,904

4 Claims. (Cl. 113—42)

1

My invention appertains in particular to the manufacture of a can-top having a ring and a lid.

The ordinary can or container of the detachable closure type has a top formed by a ring which seats the lid.

Previous to my invention, so far as I am aware, it was the usual practice to form the ring-like top by a punch and die in a press and to use a separate punch and die for forming the lid. 10 The central piercing from the ring was discarded as a slug, and a common manner of disposing of this slug was to push it upwardly out of the die, or to force it downwardly therethrough.

The paramount object of my invention is to 15 provide a punch and die for, forming a can ring and lid in a single operation, the lid being adapted for a can of a smaller size than that for which the ring is made.

A further object is to provide a combination 20 punch and die which will produce a ring and lid of the nature specified in a single press operation in which the central piercing of the ring is converted into the lid in order to utilize this slug and thus effect a substantial saving in material 25 and cost of manufacture.

A still further object is to produce a punch and die which will form the ring and the lid entirely automatically and in a manner to substantially 30 eliminate all hazard to the punch and die.

A distinctive feature of the invention is that 35 my method of manufacture produces the two parts for cans in one operation on an ordinary press in charge of a single operator. The sheet metal stock from which the two parts are simultaneously made is of the same size as customarily required for a ring.

A distinctive feature of the punch and die is that they have inner and outer cutting edges for blanking the ring and intervening forming surfaces which draw the blank inwardly from said cutting surfaces so that the formed ring may be readily pushed upwardly out of the die for ejection from the press. Additionally there is provided suitable forming surfaces centrally of the said 45 inner cutting edges of the punch and die, which form the central piercing into the lid and reduce its diameter with the result that it likewise can be readily pushed upwardly out of the die for ejection from the press.

In actual practice my invention has been found to be highly practical and economical in the manufacture of rings and lids of cans.

The selected embodiment of the invention is illustrated in the accompanying drawings, in which:

2

Fig. 1 is a central sectional view of the punch.

Fig. 2 is a central sectional view of the die used in conjunction with the punch.

Fig. 3 is a sectional view of the inverted ring and the lid formed by the punch and die.

Fig. 4 is a central section of the punch and die showing the first step of cutting the ring and lid blanks from the stock in the descent of the punch.

Fig. 5 is a similar view to Fig. 4, but shows the next step of forming the blanks into the ring and the lid.

Fig. 6 is a fragmentary perspective view of the ring, and Fig. 7 is a similar view of the lid.

Like numerals of reference indicate similar parts throughout the drawings of the invention.

In the can industry it is common to make cans and the like with closures that are secured by a friction fit between the closure itself and the top of the can. Such a top usually has a down-turned flange 10 forming a mouth receptive to the closure. Before the top is applied to the cylindrical body of the can it is common to provide it with an annular loop or channel 11, from which extends an attachment flange 12, as will be well understood in the art. The top constitutes a ring, and the closure is a lid which commonly has a central depression 13 for fitting into the mouth of the top, and a radial flange 14. It is not an object of my invention to change the form of the ring and the lid, but to provide a combination punch and die, which in one stroke of a press will form a top for a can of a certain size and a lid for a can of a smaller size, using the disc that is cut from the centre of the top. Such a top and lid are illustrated in Figs. 3, 6 and 7, and shown inverted as this is the position in which they are formed by the punch and die. A standard press is used preferably having its operating axis inclined about forty-five degrees to the vertical.

The punch, generally denoted at 15, is fitted in the crosshead of the press as by means of the element 16, and the die is mounted upon the bed by means of a bolster 17. The punch comprises the external cutting edge 18 and the internal cutting edge 19, the outer annular forming ring 20, the inner annular forming ring 21, and the knock-out member 22.

The die comprises the cutting edges 23 and 24 which correspond respectively to the cutting edges 18 and 19 aforesaid. The die also includes the outer annular forming ring 25, the central forming plug 26 and the knock-out rings 27 and 28.

The knock-out member 22 of the punch is

backed by a spring 29 and guided by the element 30 in its receding movement. The knock-out members 27 and 28 are separately backed by springs 31 and 32, and shouldered in well-known manner to limit their upward movements.

In the working stroke of the press, the first step of the operation, Fig. 4, consists in cutting from the sheet stock 33, by means of the cutting edges 18, 19, 23 and 24, the blanks from which the top A and the lid B are to be formed. The periphery 12 of the blank for the top A is clamped snugly between the annulus 20 and the knock-out ring 27 with sufficient pressure to prevent it from wrinkling, but not to prevent its being drawn inwardly in the ensuing forming operation, Fig. 5. As this blank is forced downwardly onto the forming ring 25 its medial portion is firmly gripped between a shoulder portion 34 on the member 25 and a recess 35 in the face of member 20, which shoulder portion 34 and recess 35 co-act to form the loop 11, and in so doing draw in the external diameter of the blank and also the internal diameter thereof, which assures of its being free of the cutting edges of the die in its final form. Coincidentally with the forming of said loop the flange 12 is formed, and the inner edge portion of the blank is turned up by its being forced downwardly over a shoulder 36 by the inner edge 37 of the forming ring 25 which is spaced from the forming ring 24 to clear the shoulder 36. The bending of this inner edge portion forms the flange 10 at the mouth of the top. It will now be understood that the top A is completely formed in the second step by means of the forming surfaces referred to, as the punch descends further with respect to the first step of cutting the blanks.

During the second step, the periphery of the blank for the lid B is clamped between the annular forming member 21 and the knock-out ring 28, and forced downwardly over the central forming member 26 to form the flange 14. The drawing of this flange reduces the diameter of this blank with the result that it is clear of the cutting edge 24 of the die and may be ejected without any tendency to stick in the die and damage the same.

The top A and the lid B are ejected by the knock-out devices 27 and 28 in the inverted position in which each is formed. There is no waste of material and the formed parts are free to drop freely from the press when ejected from the die. There is obviously a considerable saving both in time and labour in producing the two articles in a single operation.

Whereas the invention has been described and illustrated as applicable for the production of a single ring in conjunction with a lid, it will be manifest that it could be used for the manufacture of a multiple of rings and a lid at the same time by duplication of the ring-making parts on the punch and die.

Having disclosed the selected form of the invention it will be manifest that such changes and variations may be resorted to as come within the spirit and scope of the appended claims.

I claim:

1. A punch and die for forming in one operation a top for a can and a lid for another can of a different size, comprising means for cutting a blank from suitable stock, means for clamping the rim of said blank, means for forming an annular loop in said blank inside of said rim and an annular flange on said blank inside of said loop as said clamping means retards the

movement inwardly of the material, means for cutting out a disc from said blank, including a forming ring in the die having an inner annular cutting edge, means for clamping the rim of said disc, and means for forming a flange on said disc characterized in that it includes a central cylindrical forming member in the die, having a peripheral drawing shoulder of a less diameter than said cutting edge which provides a space receptive to an annular member on the punch having an inner drawing shoulder for co-acting with said drawing shoulder to flange the disc, said space containing a clamping ring operative to eject the disc upwardly from the die in the return stroke of the press.

2. A punch and die for forming sheet material into a can ring and a lid, the punch comprising an outer annular cutting ring, an inner annular forming ring spaced therefrom, and a central yieldable knock-out member having a clamping face, the outer edge of said outer ring having a cutting edge and the inner edge thereof having a shoulder formed by an adjacent recess in the lower surface and spaced from said cutting edge, the outer edge of said inner ring having a cutting edge and the inner edge having a drawing edge, said die comprising an outer annular cutting ring, an inner annular forming ring spaced therefrom, a central forming member spaced from the inner ring, and yieldable knock-out rings in the spaces provided between the outer ring and the inner ring and between the inner ring and the central member, the inner edge of the outer ring having a cutting edge co-acting with the cutting edge on the outer ring of the punch, the inner edge of the inner ring having a cutting edge co-acting with the cutting edge on the inner ring of the punch and that ring having a shoulder at its outer edge formed by an adjacent recess to co-act with the shoulder and recess on the outer ring of the punch to provide a loop and a flange on the can ring cut from the material, the central forming member having an outer shoulder over which the disc cut from the can ring is drawn by the drawing edge of the inner ring on the punch to form a lid.

3. A punch and die as defined in claim 2, in which in the drawing of the disc the central portion thereof is clamped by the knock-out member in the punch, and in which the edge portion of the disc is clamped by the knock-out member located between the inner ring and the central member of the die.

4. A punch and die of the class described comprising means for cutting a blank from suitable stock and for performing forming and cutting operations thereon inside its rim portion while said rim portion is yieldably clamped to retard the movement inwardly of the material, said means including a forming ring in the die having an inner annular cutting edge, the improvement including a ring in the punch inwardly of said ring having an outer annular cutting edge for co-acting with said cutting edge thereof to sever a disc from the blank and having an inner drawing shoulder, a central forming member in the die having a peripheral forming shoulder of a less diameter than said cutting edge of the first mentioned forming ring and which co-acts with said inner drawing shoulder, and a clamping ring in said space operative to upwardly eject said disc.
